US0D1066730S

(12) **United States Design Patent** (10) **Patent No.:** **US D1,066,730 S**
(45) **Date of Patent:** **** Mar. 11, 2025**

(54) **CONTAINER**

- (71) Applicant: **CSP TECHNOLOGIES, INC.**,
Auburn, AL (US)
- (72) Inventors: **Florence Grossetete**,
Niederbronn-les-Bains (FR); **Julien Klein**, Niederbronn-les-Bains (FR);
Ethan Ross Perdue, Auburn, AL (US);
Franklin Lee Lucas, Jr., Opelika, AL (US)
- (73) Assignee: **CSP Technologies, Inc.**, Auburn, AL (US)
- (**) Term: **15 Years**
- (21) Appl. No.: **29/924,094**
- (22) Filed: **Jan. 17, 2024**

Related U.S. Application Data

- (62) Division of application No. 29/909,258, filed on Aug. 3, 2023, now Pat. No. Des. 1,018,312, which is a division of application No. 29/652,773, filed on Nov. 24, 2020, now Pat. No. Des. 997,717.

(57) **CLAIM**

The ornamental design for a container as shown and described.

DESCRIPTION

FIG. 1 is a perspective view of a container of our new design;

FIG. 2 is another perspective view thereof;

FIG. 3 is a first side elevation view thereof, wherein an opposing second side elevation view is a mirror image thereof;

FIG. 4 is a top plan view thereof; and,

FIG. 5 is a bottom plan view thereof.

The dot-dashed broken lines in the drawings represent symbolic breaks forming no part of the claimed design. The symbolic breaks in the drawings indicate that any portions of the article beyond what is shown forms no part of the claimed design.

1 Claim, 4 Drawing Sheets
